WRINGER

Leonard Green, Philadelphia, Pa., assignor to
 Lovell Manufacturing Company, Erie, Pa., a
 corporation of Pennsylvania

Application January 2, 1936, Serial No. 57,077

5 Claims. (Cl. 68—269)

Power-driven wringers commonly used on washing machines present a very definite problem with relation to the possibility of the operator getting her hands caught and drawn into the wringer rolls. The present invention is designed to improve these structures by providing a mechanism which immediately operates in response to a pull of the operator against the inpulling action of the rolls, disengaging the hand from the pressure of the rolls, this being specifically accomplished, as exemplified herein, by reversing the rolls in response to a pull of the operator. Features and details of the invention will appear from the specification and claims.

15 A preferred embodiment of the invention is illustrated in the accompanying drawings as follows:—

Fig. 1 shows an elevation of a wringer.

Fig. 2 a section on the line 2—2 in Fig. 1.

20 Fig. 3 a section on the line 3—3 in Fig. 1.

Fig. 4 a section on the line 4—4 in Fig. 1.

Fig. 5 a section on the line 5—5 in Fig. 1.

Fig. 6 a view of the gear box with the cover removed.

25 The wringer frame has the usual base 1, and side stiles 2. The wringer has rolls 3 and 4, a top bar 5, and a safety release device having a latch 6 and operating bars 7. These parts are, or may be, of usual construction.

30 The wringer is swingingly supported on a substantially vertical axis so that at least a portion of the wringer frame and both rolls may be moved backwardly and forwardly. This is accomplished by a post 8 which is secured to the base of the wringer by a block 8a. The post extends through an opening 9 in an arm 10. A collar 8b is secured on the lower end of the post and locks it against removal from the opening 9. The arm 10 is carried by the usual post 11 which carries the wringer.

40 The lower roll has the usual drive shaft 12 which is journaled in bearings 13 arranged in the wringer stile. The end of the shaft is flattened at 14 and this operates in a coupling sleeve 15 secured on the end of a shaft 16. The shaft 16 is journaled in a block 17. The block is secured to the wringer stile at the power end of the wringer by a bracket 18 and bolts 19.

45 A gear box 20 is mounted on the top of the post 11. It has a removable cover 21 at the side opposite the wringer. The shaft 16 extends through a horizontal slot 22 in the wringer side of the gear box and a gear 23 is fixed on the end of the shaft 16. The gear 23 is adapted to mesh with either a gear 24 or a gear 25 as the end of

the wringer is swung forward, or back. The gears 24 and 25 are fixed on a shaft 26 which is journaled in bearings 27 in the walls of the gear box. A gear 28 drives the gear 25 and consequently the gear 24 through the shaft 26. The gear 28 is fixed on a drive shaft 29 which extends to the source of power for driving the wringer in the usual manner. The bearing block has a guide 30 which is slidably mounted between the extensions 20a and 20b on the gear box. Detents 31 10 are arranged in the surface of the guide extension 30 and these detents are yieldingly engaged by pawls 32 which are urged into the detents by springs 33 backed by screws 34, the detents, springs and screws being mounted in the extension 20a.

With the wringer set for use the gear 23 meshes with the gear away from the operator and the operator feeds the clothes into the wringer with this setting. Should the operator become caught in the rolls, the instinctive movement of the operator is to pull back, or resist the inpulling action of the rolls and this counter-pull of the operator pulls the wringer from the forward driving side to the reverse. This immediately starts the rolls in reverse and thus disengages the caught hands of the operator.

The detents 31 are arranged to hold the gear 23 in engagement with either the gear 24, or 25, or permit it to remain in neutral. The wringer, 30 therefore, may be used from either side, the direction of the gearing driving the wringer forward with the gear 23 in mesh with the gear 24, or 25, away from the operator.

In order that the wringer may be thrown into mesh, or into neutral, in a convenient manner links 35 and 36 are pivotally mounted on a bracket 37 on the arm 10. These links extend upwardly, one at each side of the bearing block 17. They are connected by a link 38 at the top and a handle 39 is provided so that these links may be readily thrown forward, or back, to throw the gear 23 into forward driving position, reverse, or neutral.

40 While it is desirable to move the frame sufficiently to reverse the rolls, the purpose of the invention may be accomplished in a measure at least by stopping the forward movement of the rolls by moving the gear 23 to the intermediate, or neutral position.

45 It will be noted that the reversing of the gears 50 effects a relief action of the wringer. That is to say the operator's hand is automatically relieved of wringer pressure by the reverse movement forcibly removing the hand. While we have shown this specific manner of relief, we do not wish to be 55

limited as to this specific manner of relief unless specified in the claims. While the invention is exemplified and described as a wringer, it is applicable in some respects to devices of a similar character.

5. What I claim as new is:

1. In a wringer, the combination of a wringer frame; wringer rolls mounted in the frame; a mounting for the frame permitting forward and backward movement of at least a portion of the frame, each roll being moved in the direction of its companion roll and in the direction of the frame with each movement of the frame; and means for driving the rolls comprising devices reversing the rolls in response to a movement of the frame.
10. 2. In a wringer, the combination of a wringer frame; wringer rolls mounted in the frame; a mounting for the frame permitting forward and backward movement of at least a portion of the frame, each roll being moved in the direction of its companion roll and in the direction of the frame with each movement of the frame; a driving means for the rolls comprising a drive shaft for one of the rolls, a reversing gear mechanism driving said shaft having opposing gears, and an intermediate gear rotatively fixed with said shaft and movable in response to a movement of the frame into mesh with one or the other of said gears, reversing the direction of movement of the rolls.
15. 3. In a wringer, the combination of a wringer

frame pivotally mounted at one end on a substantially vertical axis; wringer rolls mounted in the frame; driving means for the rolls at an end of the frame comprising a reversing mechanism; and means controlled by a swinging action of the frame on its axis reversing the mechanism.

4. In a wringer, the combination of a frame; a support for the frame; wringer rolls mounted in the frame, said rolls being provided with roll shafts; an arm extending from the support; a pivotal connection between the arm and the frame; a gear box on the support; a reversing gear in the gear box having opposing gears and an intermediate gear reversed by a shift in the mesh of the intermediate gear with the opposing gears, the relation of said gears being shifted by a movement of the frame; and shaft for one of the rolls of the wringer connected to said gear mechanism.

5. In a wringer the combination of a frame; wringer rolls mounted in the frame, said rolls being provided with roll shafts; a support for the frame; an arm extending from the support; a movable connection between the arm and the frame; a gear box on the support; a gear mechanism having one gear fixed as to location with relation to the box; and a second gear fixed on a shaft of one of the rolls and movable with the wringer frame into and out of mesh with the companion gear to stop the rolls with a movement of the wringer frame.

LEONARD GREEN.
